US00D930866S

(12) **United States Design Patent** (10) **Patent No.:** **US D930,866 S**
Shang et al. (45) **Date of Patent:** **** Sep. 14, 2021**

(54) **COMBINATION WIRELESS CHARGING LED SLIM LIGHT WITH SUPER BRIGHT TORCH LIGHT AND CHARGING STATION**

(71) Applicant: **AEC LIGHTING SOLUTIONS CO., LTD**, Shanghai (CN)

(72) Inventors: **Binhui Shang**, Shanghai (CN); **Xulong Lei**, Shanghai (CN)

(73) Assignee: **AEC LIGHTING SOLUTIONS CO., LTD**, Shanghai (CN)

(**) Term: **15 Years**

(21) Appl. No.: **29/696,359**

(22) Filed: **Jun. 27, 2019**

(30) **Foreign Application Priority Data**

Jan. 24, 2019 (CN) 201930040186.7

(57) **CLAIM**

The ornamental design for a combination wireless charging LED slim light with super bright torch light and charging station, as shown and described.

DESCRIPTION

FIG. 1 is a perspective view of the combination wireless charging LED slim light with super bright torch light and charging station showing our new design;

FIG. 2 is top plan view;

FIG. 3 is a bottom plan view;

FIG. 4 is a side elevation view of FIG. 1;

FIG. 5 is an opposite side elevation view of FIG. 1;

FIG. 6 is a front elevation view of FIG. 1; and,

FIG. 7 is a rear elevation view of FIG. 1.

The broken line showing of the combination wireless charging LED slim light with super bright torch light and charging station is for the purpose of illustrating portions of the article and forms no part of the claimed design.

1 Claim, 5 Drawing Sheets
